UNITED STATES PATENT OFFICE.

BARNA NEWMAN, OF NEW YORK, N. Y.

WATERPROOF HAT PROTECTOR.

1,417,100.

Specification of Letters Patent. Patented May 23, 1922.

Application filed February 9, 1921. Serial No. 443,601.

To all whom it may concern:

Be it known that I, BARNA NEWMAN, citizen of the United States, residing at Bronx, in the county of Bronx and State of New York, have invented certain new and useful Improvements in Waterproof Hat Protectors, of which the following is a specification.

This invention relates to a hat protector adapted to be secured upon the hat to shield the same from exposure to rain or snow.

The invention has for an object to provide a simple and inexpensive form of protecting covering which can be quickly applied to or removed from the hat, will follow the general contours of the hat, occupies little space when not in use, and will be securely held in place.

For further comprehension of the invention, and of the objects and advantages thereof, reference will be had to the following description and accompanying drawings, and to the appended claims in which the various novel features of the invention are more particularly set forth.

Fig. 1 of the drawings is a vertical sectional view of an ordinary type of men's straw hat, having my improved protector applied thereto.

Fig. 2 is a similar view showing the invention applied to the type of hat commonly known as a derby hat.

Fig. 3 is a similar view showing a modified form of the invention applied to the type of hat commonly known as a soft hat or fedora.

Fig. 4 is an underside plan view which represents any of the hats shown in Figs. 1, 2 and 3 with the modified form of the invention applied thereto.

Fig. 5 is an enlarged fragmentary section on the line 5—5 of Fig. 4.

Fig. 6 is an enlarged fragmentary section on the line 6—6 of Fig. 4.

Fig. 7 is a fragmentary horizontal section showing the drawing string device.

In constructing my improved hat protector I provide a covering 10 which may be of waterproofed cloth or thin sheet rubber and which may be shaped in a suitable manner to fit the selected one of the hats 11, 12 and 13 shown respectively in Figs. 1, 2 and 3 so as to lie in close contact with the crown and brim thereof, so that the covering will present a neat appearance when in use.

This cover 10 is formed with a marginal

portion 15 which is turned inwardly for a distance under the brim of the hat, forming both the retaining means for the cover and ensuring a complete protection of the hat. 60

When the cover is formed of some inelastic material such as waterproofed cloth it is desirable to provide a securing means for the marginal portion 15. While the latter may be radially slit at various points as indicated at 16, the securing means being applied to the inner-edge of the marginal portion to hold the same stretched under the hat brim, and comprising a novel drawing string device. 70

As shown most clearly in Figs. 5 and 6 the inner edge of the marginal portion 15 is doubled upon itself as at 17 in a manner to leave an annular recess 18 in which is located an elastic band 19 of circular cross section. This band when unstretched is of insufficient length to extend completely around the hat and has secured to the ends thereof a pair of caps 20 to which are secured in turn a pair of cords 21 of less thickness than the band 19, the ends of these cords projecting through a cutout 22 in the doubled edge 17, a pair of bushings 23 being carried in the recess or chamber 18 adjacent this cut out, through which bushings the cords 21 pass. 85 A like pair of bushings 23 may be provided adjacent certain of the slits 16 which are adapted to be engaged by the ends of the caps 20 to prevent the end of the band being accidentally drawn back as far as the said 90 slit.

In applying the covering as just described to the hat the cords 21 are pulled until the band 19 is put under suitable tension, the bushings 23 preventing the ends of the band 95 from being drawn out of the recess 18.

Having thus described my invention what I claim as new and desire to protect by Letters Patent of the United States is as follows:

1. A hat protector comprising a covering member having a marginal portion adapted to project inwardly under the brim of the hat, said marginal portion being radially slit into several sections and having its edge 101 backturned to form an annular chamber, an elastic band extending partially around said chamber, cords attached to the ends of said band, and means for preventing withdrawal of the ends of the said band from the 11 sections of the said marginal portion in which they are engaged.

2. A hat protector comprising a covering member having a marginal portion adapted to project inwardly under the brim of the hat, said marginal portion being radially 5 slit into several sections and having its edge backturned to form an annular chamber, an elastic band extending partially around said chamber, cords attached to the ends of said band, and means for preventing withdrawal 10 of the ends of the said band from the sec-

tions of the said marginal portion in which they are engaged, said means comprising caps on the ends of said band to which said cords are secured and bushings in said chamber at the ends of the sections of said marginal portion in which the ends of said band are located. 15

In testimony whereof I have affixed my signature.

BARNA NEWMAN.
